UNITED STATES PATENT OFFICE.

EDWARD C. RUTTENBERG, OF CHICAGO, ILLINOIS.

DESIGN FOR A SHADE SUPPORT.

Application filed February 3, 1923. Serial No. 5,070. Term of patent 3½ years.

To all whom it may concern:

Be it known that I, EDWARD C. RUTTENBERG, a citizen of the United States, residing at Chicago, in the county of Cook and State of Illinois, have invented a new, original, and ornamental Design for a Shade Support, of which the following is a specification, reference being had to the accompanying drawing, forming part thereof.

Fig. 1 is a top plan of the new and original design for shade support.

Fig. 2 is a side elevation of the shade support.

I claim:

The ornamental design for a shade support as shown.

EDWARD C. RUTTENBERG.
